UNITED STATES PATENT OFFICE.

ALFRED M. DEMUTH, OF CHICAGO, ILLINOIS, ASSIGNOR TO JOHN A. KELLY, OF CHICAGO, ILLINOIS.

INDIVIDUAL WORK-HOLDER ATTACHMENT FOR SLICING-MACHINES.

1,373,952.

Specification of Letters Patent.

Patented Apr. 5, 1921.

Application filed January 30, 1919, Serial No. 274,013. Renewed July 31, 1920. Serial No. 400,567.

To all whom it may concern:

Be it known that I, ALFRED M. DEMUTH, a citizen of the United States, residing at Chicago, in the county of Cook and State 5 of Illinois, have invented certain new and useful Improvements in Individual Work-Holder Attachments for Slicing-Machines, of which the following is a specification.

This invention relates in general to improvements in slicing machines, but more particularly relates to an improved article support adapted to rest upon or be connected with the feeding plate of the machine so that the uprights and pins or prongs carried by the feeding plate will not interfere with the ready attachment or removal of the supplemental support, thereby adapting the article support for an individual article holder, rendering it unnecessary to remove 15 the article from the support after being once placed thereon.

Heretofore considerable difficulty and inconvenience has been experienced with slicing machines in that after an article has 20 once been removed it is impossible to place the same into the machine again so that the first few slices will be unbroken and of a uniform thickness. Furthermore, unsanitary conditions are accentuated by the constant handling of the article which is necessary to change from one article to another.

To overcome these objections and difficulties and to provide an improved attachment 25 of this character with which the clamping bar now employed in slicing machines will coöperate, is another object of the present invention.

A further object is to provide an improved article support of this character 30 which may be shaped from a single piece of sheet material and in one operation.

To the attainment of these ends and the accomplishment of other new and useful 35 objects as will appear, the invention consists in the features of novelty in substantially the construction, combination and arrangement of the several parts, hereinafter more fully described and claimed and shown 50 in the accompanying drawings illustrating this invention and in which—

Figure 1 is an elevation of a portion of a slicing machine having an attachment con-

nected therewith and constructed in accordance with the principles of this invention. 55

Fig. 2 is a sectional view as taken on line 2—2 Fig. 1.

Fig. 3 is a detail perspective view of the individual work holder attachment.

Fig. 4 is an end elevation of Fig. 3. 60

Fig. 5 is a transverse vertical section of the attachment showing a different manner of securing the impalement elements thereto.

Fig. 6 is a view similar to Fig. 3 of a modified form of the invention. 65

Fig. 7 is a sectional view taken on line 7—7 Fig. 6.

Referring more particularly to the drawings the numeral 10 designates a reciprocating carrier adjacent the edge 11 of which the 70 knife 12 operates. Mounted upon the carrier 10 is a feeding table 13 having uprights 14—15 projecting thereabove and upon which uprights a clamping bar 16 operates. The feeding table 13 is adapted for bodily 75 reciprocating movement with the carrier 10 and is also adapted for an intermittent forward movement with relation to the carrier 10, as is usual in machines of this character.

The attachment or individual work holder 80 or support of the present invention embodies a body portion 17 having its sides 18 deflected at an angle thereto to project thereabove for any desired or suitable distance, the extremities of these deflected portions 18 are bent laterally outwardly as at 19. The upwardly deflected portions 18 and the laterally deflected portions 19, preferably terminable short of the forward edge 20 of the body portion or base of the attachment, and an open recess 21 is provided in the forward end of the portion 19, to open through the said end. 85

The forward edge of the base or body of the support is provided with a plurality of 90 recesses 22 opening through said edge and a plurality of slots or openings 23—24—25 are provided through the body of the support, intermediate the forward and rear edges thereof. 100

Impalement elements 26 are connected with the body portion 17 of the attachment and within the confines of its edges. These elements 26 may be formed in any desired or suitable manner. As shown in Figs. 3 105 and 4 they may be formed as prongs cut

from the body portion and deflected as shown to project upwardly so that they will impale the article when the latter is placed upon the support. If desired however these 5 impalement elements may be formed separately as at 27 and secured to the support in any suitable manner.

Handles 28 by means of which the support may be transported or attached to and 10 removed from the machine may be provided, and these handles may be formed in any suitable manner either integrally therewith or separately and attached thereto. If formed integrally, they may be formed from 15 the laterally deflected portions 19 of the support by cutting a portion of the support and shaping the cut portions into handles as shown in Fig. 3.

In use the attachment may be placed in 20 the machine and upon the feeding table 13 by grasping the handles 28 and positioning the forward edge 20 so that the impalement elements 29 which are carried by the feeding table 13 adjacent its forward edge, will enter the recesses 22 and 25 the uprights 14—15 will enter the respective recesses or seats 21. When in this position the slots or openings 23—24—25 will be respectively positioned over the impalement elements 30—31—32 which are usually 30 carried by the feeding table 13. The handles 28 may then be released so that the attachment will rest upon the feeding table 13 and will be held against accidental displacement 35 with respect thereto by means of the recesses and slots coöperating with the impalement elements 29—30—31—32 carried by the feeding table, and also by means of the upwardly deflected walls 18 of 40 the attachment coöperating with the respective shoulders 33 of the feeding table 13.

When in position, the article may then be placed upon the supplemental support so that the elements 26 will impale the 45 article and the clamping bar 26 may then be lowered upon the uprights 14—15 so as to engage and clamp the article.

The body of the attachment or supplemental support may be of any desired thickness and may be of such a size as to permit the extremities of the impalement elements 29—30—31—32 to project thereabove so as to also engage the article, or may be of a suitable thickness as to prevent these 55 impalement elements which are carried by the feeding table 13 from engaging the article when the attachment is in position.

The attachment is also constructed of a single piece of sheet material and when 60 constructed in the manner as shown in Fig. 3 may be bent into shape and all parts thereof formed in a single operation.

When it is desired to remove the article from the machine to be replaced by another 65 article, all that is necessary is to raise

the clamping bar 18 on the uprights 14—15 when the supplemental support may be grasped by the handles 28 and lifted bodily, with the article thereon from the machine, thereby serving as an individual article 70 holder and rendering it unnecessary to handle the article and also insuring the proper positioning of the article and support back into the machine so that the first few slices will be unbroken and of a uniform thickness. The upwardly projecting walls 18 along the sides of the support also serve 75 as a means for holding the article in proper position.

In the form of the invention shown in 80 Figs. 6 and 7 a portion of the body 17 of the holder is cut away on opposite sides of its center and bent upwardly as at 33 to form upwardly projecting curved walls on opposite sides of the impalement elements. These walls coöperate with the impalement elements to hold the article against displacement.

If desired the edges of the walls 33 may be cut away as at 34 so as not to interfere with the operation of the clamping element 16, in the event that it is necessary to bring the clamping element in close proximity to the holder.

In addition to the impalement elements 95 26, other impalement elements 35 may be provided which may also be cut from the body 17 and deflected upwardly. These impalement elements 35 are so shaped that their face will be arranged transversely with 100 respect to the face of the impalement elements 26 and all of the elements coöperate to form a locking means for holding the article in position.

With this improvement it will be manifest 105 that any number of these supplemental holders or work supports may be provided to be interchanged in the machine and the articles may be interchanged without handling the article.

It will be manifest that this improved individual work holder can be readily applied to any machine now on the market without altering in the slightest degree the construction of any of the parts of the slicing machine.

While the preferred form has been herein shown and described, it is to be understood that various changes may be made in the details of construction and in the 120 combination and arrangement of the several parts without departing from the spirit of this invention.

What is claimed as new is:—

1. A device of the character described, 125 embodying a main support, an upright connected therewith, a supplemental support, and a clamping element movable upon the upright and adapted to coöperate with the supplemental support, said supplemental sup- 130

port being attachable and removable at will and while the said clamping member is connected with the upright.

2. A device of the character described, 5 embodying a main support, an upright connected therewith, a supplemental support, and a clamping element movable upon the upright and adapted to coöperate with the supplemental support, said supplemental sup-

10 port being attachable and removable at will and while the said clamping member is connected with the upright, the said supplemental support being shaped from a single piece of sheet material.

15 3. In combination, a slicing machine embodying a main article support, impalement elements projecting thereabove, an upright extending above the support, a supplemental support, and a clamping element adapted to 20 coöperate with the supplemental support, said supplemental support being adapted to be placed upon and removed from the main support at will and while the clamping member is on the upright, said supplemental sup- 25 port being provided with portions shaped to receive the impalement elements which are connected with the main support.

4. In combination, a slicing machine embodying a main article support, impalement 30 elements projecting thereabove, an upright extending above the support, a supplemental support, and a clamping element adapted to coöperate with the supplemental support, and provisions whereby said supplemental 35 support may be placed upon the main support at will and while the clamping member is on the upright, the said provisions embodying an open seat upon the supplemental support adapted to receive the upright.

40 5. In combination, a slicing machine embodying a main article support, impalement elements projecting thereabove, an upright extending above the support, a clamping element movable upon the upright, a supple- 45

mental support with which the clamping element is adapted to coöperate, and provisions whereby the supplemental support may be placed upon the main support and removed at will and while the clamping ele- 50 ment is on the upright, the said provisions embodying recesses to receive the impalement elements that are on the main support, some of the recesses being arranged along and opening through the front edge of the 55 supplemental support.

6. In combination, a slicing machine embodying a main article support, impalement elements projecting thereabove, an upright extending above the support, a clamping element movable upon the upright, a supplemental support with which the clamping element is adapted to coöperate, provisions 60 whereby the supplemental support may be placed upon the main support and removed at will and while the clamping element is

on the upright, the said provisions embodying recesses to receive the impalement elements that are on the main support, some of the recesses being arranged along and opening through the front edge of the supplemental support, and impalement elements carried by and projecting above the supplemental support. 70

7. In combination, a slicing machine embodying a main article support, impalement 75 elements projecting thereabove, an upright extending above the support, a clamping element movable upon the upright, a supplemental support with which the clamping element is adapted to coöperate, provisions 80 whereby the supplemental support may be placed upon the main support and removed at will and while the clamping element is on the upright, the said provisions embodying recesses to receive the impalement elements 85 that are on the main support, some of the recesses being arranged along and opening through the front edge of the supplemental support, and means carried by the supplemental support for securing an article 90 thereto.

8. In combination, a slicing machine embodying a main article support, impalement elements projecting thereabove, an upright 95 extending above the support, a clamping element movable upon the upright, a supplemental support with which the clamping element is adapted to coöperate, provisions whereby the supplemental support may be placed upon the main support and removed 100 at will and while the clamping element is on the upright, the said provisions embodying recesses to receive the impalement elements that are on the main support, some of the recesses being arranged along and opening through the front edge of the supplemental support, and handles connected with the supplemental support for transporting the same. 105

9. A freely attachable and removable individual article holder for slicing machines, said holder embodying a supporting plate provided with one or more post seats opening through one edge of the plate and having impalement element receiving recesses also 110 opening through one edge of the plate. 115

10. A freely attachable and removable individual article holder for slicing machines, said holder embodying a supporting plate provided with one or more post seats opening through one edge of the plate and having impalement element receiving recesses also opening through one edge of the plate, and impalement elements carried by and projecting above the said plate within the 120 confines of the edges of the plate. 125

11. A freely attachable and removable individual article holder for slicing machines, said holder embodying a supporting plate provided with one or more post seats 130

- opening through one edge of the plate and having impalement element receiving recesses also opening through one edge of the plate, and handles connected with the said 5 plate.
12. A freely attachable and removable individual article holder for slicing machines, said holder embodying a supporting plate provided with one or more post seats 10 opening through one edge of the plate and having impalement element receiving recesses also opening through one edge of the plate, said plate being constructed of a single piece of sheet material formed into 15 shape.
13. A freely attachable and removable individual article holder for slicing machines, said holder embodying a supporting plate provided with one or more post seats 20 opening through one edge of the plate and having impalement element receiving recesses also opening through one edge of the plate, said plate being also provided with impalement element receiving openings 25 within the confines of the edges of the plate.
14. A freely attachable and removable individual article holder for slicing machines, said holder embodying a supporting plate provided with one or more upright 30 receiving seats opening through one edge of the plate and having impalement element receiving recesses opening through one edge of the plate, the sides of the plate projecting upwardly from the plate.
15. A freely attachable and removable individual article holder for slicing machines, said holder embodying a supporting plate provided with one or more upright receiving seats opening through one 35 edge of the plate and having impalement element receiving recesses opening through one edge of the plate, the sides of the plate projecting upwardly from the plate, the whole being constructed from a single piece 40 of sheet material, and handles connected with the plate.
16. An individual article holder attachment for slicing machines embodying a supporting plate having a recessed edge, and 50 impalement prongs projecting above the plate all constructed from a single sheet of sheet material.
17. An individual article holder attachment for slicing machines embodying a supporting plate having a recessed edge, and 55 prongs cut from said plate and deflected upwardly, the face of some of said prongs being disposed transversely with respect to other of said prongs.
18. A freely attachable and removable individual article holder for slicing machines embodying a supporting plate having a recessed edge, means carried by the plate within the confines of the edges thereof and curving upwardly therefrom for receiving and holding the article, and article impalement elements carried by the plate. 60
19. A freely attachable and removable individual article holder for slicing machines embodying a supporting plate having a recessed edge, means carried by the plate within the confines of the edges thereof and curving upwardly therefrom for receiving and holding the article, and article impalement elements carried by the plate, 65 all of said parts being of an integral construction. 70
20. A freely attachable and removable individual article holder for slicing machines embodying a supporting plate having a recessed edge, a portion of the plate being cut and deflected upwardly to form a seat for the article, and prongs cut from the plate and also being deflected upwardly, all 75 of the parts being shaped from a single piece of sheet material. 80
21. An individual article holder for slicing machines embodying a supporting plate, having a recessed edge, and impalement elements carried by the plate, said holder being freely attachable to and removable from a slicing machine and while all of the coöperating parts of the slicing machine are 90 intact.
22. An individual article holder for slicing machines embodying a supporting plate, and impalement elements carried by the plate, said plate and elements being constructed from a single piece of sheet material and being attachable to and removable 95 from a slicing machine and while the coöperating parts of the slicing machine are intact. 100
23. An individual article holder for slicing machines embodying a supporting plate, and impalement elements carried by the plate, said plate being freely attachable to and removable from the machine while the coöperating parts of the machine are intact, said impalement elements being formed so 105 that the face of some of the said elements will stand transversely with respect to the face of other of the said elements. 110
- In testimony whereof I have signed my name to this specification, on this 24th day 115 of January, A. D. 1919.

ALFRED M. DEMUTH.
